Attorney, Agent, or Firm—Holme, Roberts & Owen, LLP

[57] CLAIM

The ornamental design for a rattle, as shown.

DESCRIPTION

FIG. 1 is a perspective view of a first embodiment of a rattle showing my new design;

FIG. 2 is a front elevation view of the first embodiment thereof, with the back elevation view identical to the front elevation view;

FIG. 3 is a right side view of the first embodiment thereof, where the left side view is identical to the right side view;

FIG. 4 is a top plan view of the first embodiment thereof;

FIG. 5 is a bottom plan view of the first embodiment thereof;

FIG. 6 is a front cross sectional view of the first embodiment showing an unobstructed view of the shape of the individual elements;

FIG. 7 is a front elevation view of the first embodiment of a rattle in an alternate position; and,

FIG. 8 is a cross sectional view of the first embodiment of a rattle in the alternate position which shows the relative positions of the individual elements.
